(57) **CLAIM**

The ornamental design for a collapsible container, as shown and described.

DESCRIPTION

FIG. 1 is a front perspective view of a collapsible container of the claimed design;

FIG. 2 is a first side view thereof;

FIG. 3 is a second side view thereof;

FIG. 4 is a third side view thereof;

FIG. 5 is a fourth side view thereof;

FIG. 6 is a first end view thereof;

FIG. 7 is a second end view thereof;

FIG. 8 is a first side view thereof in a collapsed orientation;

FIG. 9 is a second side view thereof in a collapsed orientation;

FIG. 10 is a top view thereof in a collapsed orientation;

FIG. 11 is a front perspective view of another embodiment of a collapsible container;

FIG. 12 is a first side view thereof;

FIG. 13 is a second side view thereof;

FIG. 14 is a third side view thereof;

FIG. 15 is a fourth side view thereof;

FIG. 16 is a first end view thereof;

FIG. 17 is a second end view thereof;

FIG. 18 is a first side view thereof in a collapsed orientation;

FIG. 19 is a second side view thereof in a collapsed orientation;

FIG. 20 is a top view thereof in a collapsed orientation;

FIG. 21 is a front perspective view of another embodiment of a collapsible container;

FIG. 22 is a first side view thereof;

FIG. 23 is a second side view thereof;

FIG. 24 is a third side view thereof;

FIG. 25 is a fourth side view thereof;

FIG. 26 is a first end view thereof;

FIG. 27 is a second end view thereof;

FIG. 28 is a first side view thereof in a collapsed orientation;

FIG. 29 is a second side view thereof in a collapsed orientation; and,

FIG. 30 is a top view thereof in a collapsed orientation.

The broken lines in the drawings depict portions of the collapsible container that form no part of the claim.
